BAFFLE TYPE MUFFLER WITH
RETROVERTED FLOW

Patrick J. May, San Francisco, Calif.

Application December 8, 1945, Serial No. 633,760

3 Claims. (Cl. 181—53)

1

My invention relates to improvements in internal combustion engine mufflers, and more particularly to a two-piece muffler housing comprising upper and lower sections in which are positioned a series of perforated baffle plates and deflector plates, together with a pair of baffles at the rear end of the muffler which traps any exhaust noises and simultaneously directs the exhaust gasses towards the front of the muffler and finally over a rearwardly extending solid baffle to the exhaust end of the muffler.

An object of my invention is to provide an improved form of muffler which will be substantially rectangular in cross section and which will comprise a plurality of perforated baffles and a baffle trap, whereby the exhaust noises incident to an internal combustion engine will be silenced, and at the same time the construction of the muffler will prevent any trapping or pockets of the exhaust gasses in the muffler, thereby enhancing the efficient operation of the internal combustion engine to which it is attached.

A further object of my invention is to provide a highly efficient form of muffler for an internal combustion engine which will reduce back pressure and pocketing of the exhaust gasses to a minimum, while muffling and silencing the exhaust noises from the internal combustion engine to which the muffler is attached.

Other objects will appear as the description proceeds.

In the accompanying drawings which form a part of my application,

Figure 1 is a top plan view of my improved muffler;

Figure 2 is a side elevation of my improved muffler;

Figure 3 is an end view of my muffler;

Figure 4 is a longitudinal sectional view through the muffler;

Figure 5 is a transverse sectional view taken on the line 5—5 of Figure 4;

Figure 6 is a transverse sectional view taken on the line 6—6 of Figure 4;

Figure 7 is a partial sectional view taken on the line 7—7 of Figure 4; and

Figure 8 is a sectional view taken on the line 8—8 of Figure 4.

Like characters of reference are used throughout the following specification and the accompanying drawings to designate corresponding parts.

In carrying out my invention, I provide a muffler housing having an upper section 1 and a lower

2

section 2 substantially rectangular in shape and held together by means of the beads 3 on the opposite sides of the upper section and the flanges 4 on the opposite sides of the lower section, which 5 are crimped together to form a substantially rigid muffler housing. The opposite ends of the muffler housing are tapered as at 5 and 6 and terminate in the cylindrical ends 7 and 8, which will be connected respectively to the exhaust manifold 10 of an internal combustion engine (not shown), and to the exhaust tail pipe (also not shown).

At the inlet end of the muffler housing and secured to the inner surfaces of the upper and lower sections by spot welding 9, I have provided 15 the rearwardly extending converging perforated baffles 10 and 11 which are slightly bowed transversely and extend the full width of the muffler housing at that point. These baffles 10 and 11 are bent adjacent their rear ends to form the 20 flattened parallel extending terminal ends 12 and 13 and are slightly spaced to direct the exhaust gasses rearwardly along the interior of the muffler.

A second pair of perforated baffle plates 14 and 15 extend transversely of the muffler sections 1 and 2, and are suitably secured thereto and converge or slope toward each other from the front end of the muffler toward the rear thereof, and terminate in the spaced parallel extending terminal ends 16 and 17, which are in alignment 25 with the terminal ends 12 and 13 of the baffle plates 10 and 11, but to the rear thereof.

A transversely extending deflector plate 18 is spot welded at 19 to the opposite sides of the upper muffler section 1, and is formed with the perforations 20 adjacent its forward end and the perforations 21 adjacent its rear end. The plate 18 slopes downwardly from its front end to its rear end and is bent upwardly as at 22 adjacent its rear end. The purpose of the deflector plate 18 is to prevent trapping or pocketing of the exhaust gasses in the front end of the muffler, particularly between the baffle plate 14 and the deflector plate 18.

A forwardly sloping deflector plate 23 extends 45 transversely of the muffler housing from a point a short distance below the top of the upper muffler section 1 where it is spot welded at 24, to the bottom of the lower muffler section 2, thereby acting to direct all of the exhaust gasses rearwardly and to discharge the said gasses through the restricted opening formed by the upper rear end of the deflector plate 23 and the adjacent top of the top muffler section 1.

A short forwardly sloping deflector plate 25 50 extends transversely across the muffler housing 55

below the deflector plate 23 and extends parallel with the said plate 23. The plate 25 extends at its rear end from a point approximately half the distance between the top and bottom of the muffler housing to the bottom surface of the housing at its forward or lower end, and is spot welded as at 26 to the sides of the said muffler housing.

Interposed between the deflector plates 23 and 25 are a pair of cooperating baffle or deflector plates 27 and 28, which act as a cushion or trap for the exhaust sounds and stops the acoustics between the said plates 27 and 28. The plate 27 is spot welded at 29 to the top of the muffler housing and extends downwardly therefrom and is bent at right angles thereto, and extends forwardly to a point intermediate the deflector plates 23 and 25, where it is again bent to extend parallel with and between the said plates 23 and 25.

The plate 27 is also spot welded at 30 and 31 to the sides of the muffler housing, as clearly shown in Figure 4 of the drawings.

The baffle or deflector plate 28 is spot welded at 32 to the top of the muffler housing and extends downwardly therefrom and is bent at right angles to extend forwardly to a point between the deflector plates 23 and 27. Perforations 33 are formed through the upper portion of the plate 28 so that the remaining exhaust noises will be cushioned as they pass through these perforations, and the noises will be stopped or trapped between the plates 28 and 29. The flow of exhaust gasses will then be directed forwardly between the deflector plates 23 and 29, and then rearwardly between the plates 25 and 29, where the gasses will pass out of the muffler to and through the tail pipe (not shown).

From the foregoing description it will be apparent that I have devised a highly efficient form of muffler which will efficiently silence the noises from an internal combustion motor, and will reduce pocketing or back pressure of the exhaust gasses to a minimum. By inspection of Figure 4 of the drawings it will be apparent that the exhaust gasses enter the front end 7 of the muffler and pass through the perforations in the baffle plates 10 and through the restricted opening between the transverse parallel tail ends 12 and 13 of the baffles 10 and 11. It will be understood that some of the gasses pass through the perforations and some of the gasses pass between the tail ends 12 and 13. The gasses will then be deflected rearwardly where they will pass through the perforated deflector plates or baffles 14 and 15, and also some of the gasses will pass through the restricted opening between the parallel transverse tail ends 16 and 17 of the said baffles 14 and 15.

The exhaust gasses will then be directed to and through the deflector plate 18 and along the upper surface of the deflector plate 23 and from this point through the restricted opening at the rear end of said deflector plate 23 and the top of the muffler housing. The deflector plate 18 with its arrangements of perforations 20 and 21 serves to prevent any pocketing or trapping of the exhaust gasses at this forward end of the muffler and the upturned tail end 22 of the deflector plate 18 will direct the exhaust gasses toward the restricted openings formed by the deflector plate 23 at the top of the muffler housing as hereinbefore described.

The flow of exhaust gasses will pass through the perforations 33 in the plate or baffle 28 and into the space between the said plate or baffle 28 and the baffle 27, whereupon the gasses will be

directed forwardly and down between the forward portion of the baffle 27 and the deflector plate 23. From this point the gasses will then be directed rearwardly between the baffles or deflector plates 25 and 27 to the rear end of the muffler where they will pass from the muffler and to and through the tail pipe (not shown). As hereinbefore described and mentioned the formation of the deflector of baffle plates 28 and 29 with the perforation 33 in the plate 28 serves to cushion and stop the exhaust sounds so that practically no noise will be emitted from the rear end of the muffler. It has been found that internal combustion engines equipped with mufflers formed in accordance with my invention, are highly efficient, and due to the fact that there is substantially no back pressure in the muffler, I have been able to run more miles per gallon of gasoline when using this muffler than possible when using mufflers now on the market.

While I have described and illustrated my preferred form of invention, it will be understood that I do not intend to limit myself to this specific construction, as many minor changes in detail of construction may be resorted to without departure from the spirit of the invention.

Having thus described my invention, what I claim as new and desire to secure by Letters Patent of the United States is:

1. An engine muffler comprising a housing having upper and lower sections connected along their opposite sides, a tortuous path of travel for exhaust gases defined in said housing and including nested pairs of rearwardly converging perforated baffle plates positioned adjacent the front ends of said muffler and terminating in restricted longitudinally aligned end inlet passages, a pair of cooperating angular deflector baffle plates positioned adjacent the rear of said muffler, one of said last mentioned plates being perforated, a rearwardly sloping perforated deflector plate positioned adjacent said front baffle plates and having an upwardly angularly extended terminal end disposed adjacent the inlet passageways for directing the exhaust gasses to said rear baffle plates, an elongated upwardly sloping imperforate deflector plate extending rearwardly from the bottom of the muffler housing to a point adjacent the rear baffle plates, said deflector plate being spaced from the top of the muffler housing thereby forming a restricted opening through which exhaust gasses will be directed toward the rear baffle plate, said angular terminal and elongated plate defining a selected rearwardly extending passageway and an upwardly sloping short deflector plate extending between the sides of the muffler housing from the bottom of the muffler housing to a point below the rear baffle plate, said short deflector plate being parallel to said elongated deflector plate and lying below the same forming a restricted outlet passage.
2. An engine muffler comprising a housing having upper and lower sections connected along their opposite sides, a tortuous path of travel for exhaust gases defined in said housing and including a plurality of nested rearwardly converging perforated baffle plates positioned adjacent the front end of said housing and terminating in restricted longitudinally aligned inlet passageways, a pair of cooperating angular deflector baffle plates positioned adjacent the rear end of said housing at the top thereof, one of said last named baffle plates being perforated, a rearwardly sloping deflector plate positioned intermediate said front and rear baffle plates and having an

upwardly extending terminal end spaced from said housing and disposed adjacent the inlet passageways to direct the exhaust gases toward said rear baffle plates, an elongated upwardly sloping deflector plate extending rearwardly from the bottom of the housing to a point adjacent the rear baffle plates and spaced from the top of the housing to define a restricted passageway at the top of the housing to the rear baffle plates and an upwardly sloping short deflector plate positioned parallel to and below the elongated deflector plate.

3. An engine muffler comprising a housing having opposed ends provided with longitudinally aligned openings defining an inlet and an outlet, nested pairs of rearwardly converging perforated baffle plates positioned adjacent the inlet end of the housing and terminating in restricted longitudinally aligned inlet passageways, a pair of cooperating angular inner and outer deflector baffle plates positioned adjacent the outlet end of the housing, said inner plate being perforated, a rearwardly and downwardly sloping perforated deflector plate positioned in front of said nested inlet baffle plates and having an upwardly extended terminal end disposed adjacent the inlet passageways in the plates, said terminal end being adapted to direct the exhaust gases to said outlet baffle plates, an elongated upwardly sloping deflector plate positioned below the nested inlet baffle plates and extending rearwardly from the bottom of the housing to a point spaced from the top adjacent the outlet baffle

plates to define a restricted opening through which the exhaust gases will be directed towards the outlet baffle plates, said terminal end and elongated baffle plate being disposed in substantial parallelism and defining a restricted passageway, an upwardly sloping short deflector plate extending between the sides of the housing from the bottom thereof to a point below the outlet baffle plates, said short deflector plate being parallel to said elongated plate and positioned below the same, and said outer outlet baffle plate being provided with an angular downwardly extending end directed between the short deflector plate and elongated deflector plate.
